UNITED STATES PATENT OFFICE.

PORTR H. BRACE, OF PITTSBURGH, PENNSYLVANIA, ASSIGNOR TO WESTINGHOUSE ELECTRIC & MANUFACTURING COMPANY, A CORPORATION OF PENNSYLVANIA.

MEANS FOR REPLENISHING THE ELECTROLYTE OF ELECTROLYTIC CELLS.

Application filed November 13, 1919. Serial No. 337,682.

To all whom it may concern:

Be it known that I, PORTER H. BRACE, a citizen of the United States, and a resident of Pittsburgh, in the county of Allegheny and State of Pennsylvania, have invented a new and useful Improvement in Means for Replenishing the Electrolyte of Electrolytic Cells, of which the following is a specification.

10 My invention relates to electrolytic cells and, more particularly, to apparatus of this character employed in the production of metals by the electrolysis of fused salts, and it has, for its primary object, the provision 15 of means for maintaining an electrolyte of constant composition and quantity.

Heretofore, in order to maintain electrolytes of constant composition and quantity during the electrolysis of fused salts, additions have been made to the electrolyte in various ways, but it has been very difficult to do this satisfactorily or to make the addition continuously, as is desirable, particularly where hydroscopic materials are being 25 employed.

One object of my present invention is to secure continuous replenishment of the electrolyte with a minimum disturbance of the same and with a minimum interference with 30 the operation of the cell.

Another object which I have in view is the addition of material to the electrolyte by the utilization of a continuously melting or dissolving body of the desired material 35 to be added.

In this connection, my invention further comprises the provision of a specially designed electrode which is, preferably, the anode and which is so formed as to serve as 40 a means for replenishing the electrolyte.

Another object accomplished by my invention consists in the provision of means for controlling the rate of addition of material to the electrolyte.

45 With these and other objects in view, my invention will be more fully described, illustrated in the single figure of the drawing which is a diagrammatic sectional view of a preferred form of my invention, and then 50 specifically pointed out in the claims.

In order to ensure a complete and accurate understanding of my invention and the method of practising it, I have illustrated a conventional form of electrolytic cell, such 55 as is commonly employed in the electrolysis

of fused salts and, particularly, salts of the alkaline-earth metals comprising calcium, barium and strontium. The cell may comprise a cup or container 1 for the fused salt 2 being treated, a cathode 3 and an anode 4. 60 The cathode may preferably be supported by an arm 5 which is insulated from, and adjustably carried by, an adjusting screw 7 mounted for free turning movement, whereby the cathode may be raised as a deposit 65 of metal is formed thereon.

The anode 4, in like manner, may be supported by an arm 8 insulated from, and adjustably supported by, an adjusting screw 9 in such manner that it may be raised or lowered at will.

70 My present invention comprehends the provision of a special form of anode so constructed that it may constitute means for constantly replenishing the electrolyte of the 75 cell. For this purpose, the anode 4 may be formed, in its upper portion, with an axial chamber 10 adapted to receive a solid body or rod 11 of the material to be added to the electrolyte. A reduced extension or passage 80 12 may lead from the lower end of this chamber, terminating short of the lower end of the electrode, and a plurality of radial and upwardly inclined branch passages 13 may lead from the lower end of the passage 85 12 through the wall of the electrode. The open end of the anode may be provided with a suitable cover to prevent the access of air when hydroscopic salts are used.

80 The operation of an electrolytic cell embodying my invention will be readily understood from the foregoing explanation and need be only briefly described. Obviously, the heat generated at the lower portion of the electrode constituting the anode of the 90 cell will act to melt or dissolve the body or rod of electrolyte material 11 contained in the electrode so that this material will be gradually discharged into the electrolyte through the passages 12 and 13. The rate at 95 which the electrolyte material is supplied to the electrolyte from the source 11 will, of course, be dependent upon the amount of heat generated at the electrode and this heat may be governed by adjustably raising or 100 lowering the electrode, to vary the extent to which it is immersed in the electrolyte. The upward inclination of the branch passages 13 prevents any gases, which may be evolved, from passing into the interior of the 110

electrode, and, consequently, this feature is not essential in all instances.

Although I have illustrated a preferred embodiment of my invention and described it in detail, it will be appreciated that various ways of supplying electrolyte material, through the use of a continuously melting or dissolving body of such material, may be provided and that anodes of various constructions may be formed to adapt them for this purpose. No limitations are, therefore, to be imposed upon my invention other than those necessitated by the prior art or indicated in the appended claims.

16. I claim as my invention:

1. The combination with an electrolytic cell including an electrolytic bath and electrodes, of means, operable through heat generated at an electrode, for liquefying electrolyte material and supplying it to the bath.

2. The combination with an electrolytic cell including an electrolytic bath and electrodes, of means, operable through heat generated at an electrode, for liquefying electrolyte material and continuously supplying it to the bath.

3. The combination with an electrolytic cell including an electrolytic bath and electrodes, of means co-operating with one electrode for supplying liquefied electrolyte material to the bath.

4. The combination with an electrolytic

cell including an electrolytic bath and electrodes, of means co-operating with one electrode for supplying liquefied material to the bath and means for varying the rate of supply of such material.

5. The combination with an electrolytic cell including an electrolytic bath and a cathode movable toward and away from the bath, of an anode provided with a chamber and with a passage opening from the chamber through the lower portion of the anode.

6. The combination with an electrolytic cell including an electrolytic bath and a cathode movable toward and away from the bath, of an anode provided with a chamber and with a passage opening from the chamber through the lower portion of the anode, and means for adjustably raising and lowering the anode to vary the extent to which it is immersed in the bath.

7. An electrode for use in the electrolysis of fused salts comprising a body provided with a chamber adapted to receive solid electrolyte material and further provided with a passage leading from the chamber and adapted to communicate with an electrolytic bath.

In testimony whereof, I have hereunto 60 subscribed my name this 29th day of Oct., 1919.

PORTER H. BRACE.
